UNITED STATES PATENT OFFICE.

ALLEN BAGGS DOWELL, OF CARBONDALE, ILLINOIS.

DEVICE FOR SINKING THROUGH SOFT STRATA, SUCH AS MUCK, SAND, &c.

No. 912,941.

Specification of Letters Patent.

Patented Feb. 16, 1909.

Application filed January 20, 1908. Serial No. 411,851.

To all whom it may concern:

Be it known that I, ALLEN BAGGS DOWELL, a citizen of the United States, residing at Carbondale, in the county of Jackson and

5 State of Illinois, have invented certain new and useful Improvements in Devices for Sinking Through Soft Strata, such as Muck, Sand, &c., of which the following is a specification.

10 This invention relates to an improved device for sinking or excavating through soft strata consisting of muck, sand, quicksand or the like; and it has for its object to provide a simple and improved apparatus which 15 shall prevent the dirt from caving into the newly - made excavation, thus dispensing with the necessity of removing other dirt than that required to make the excavation, proper.

20 Another object of the invention is to provide a shoe or casing, equipped with doors or closures to regulate the passage of the material to be excavated, and also equipped with a shelf or bracket, termed a "jack-seat" adapted to support a plurality of screw- or pneumatic jacks or equivalent implements, whereby the apparatus may be forced in a downward direction in the process of making the excavation.

25 Still further objects of the invention are to simplify and improve the construction and operation of this class of devices.

30 With these and other ends in view which will readily appear as the nature of the invention is better understood, the same consists in the improved construction and novel arrangement and combination of parts which will be hereinafter fully described and particularly pointed out in the claims.

35 In the accompanying drawings has been illustrated a simple and preferred form of the invention; it being however understood that no limitation is necessarily made to the precise structural details therein exhibited, 40 but that changes, alterations and modifications within the scope of the invention may be resorted to when desired.

In the drawings—Figure 1 is a top plan view of a device embodying the invention.

45 Fig. 2 is a vertical transverse sectional view taken on the plane indicated by the line 2—2 in Fig. 1. Fig. 3 is a vertical sectional detail view taken on the plane indicated by the line 3—3 in Fig. 1.

Corresponding parts in the several figures 55 are denoted by like characters of reference.

The improved device consists essentially of a shoe or casing C which, in its general outline, may be square, rectangular, circular, or of any convenient or appropriate shape or 60 outline, which will be governed mainly by the nature of the excavation that is to be made or the character of the work to be performed. The casing is preferably constructed of metallic plates, such as boiler-plate, and bars and angle-beams, of suitable form.

In the accompanying drawings has been illustrated a rectangular casing the outer walls of which are designated 5; this casing 70 is subdivided by longitudinally disposed beams or plates 6 and transverse beams or plates 7, into a plurality of cells or compartments 8, 8; the plates 6 and 7 intersecting each other at right angles, as shown. 75 The partition plates 6 and 7 have been shown as being approximately one-half the height of the walls 5, although these proportions may be varied at will. The partition plates 80 6 and 7 are reinforced adjacent to their upper and lower edges by angle-beams 9 and 10, and similar angle-beams 10' are secured at the lower edges of the wall-plates 5; the angle-beams 10 at the lower ends of the compartments serve to support upwardly- 85 opening pressure-doors or closures 11, which, when closed or folded, rest upon the said angle-beams and are thereby prevented from swinging in a downward direction. Each compartment is provided with two doors 90 coöperating to form a complete closure, said doors being mounted by means of strap-hinges 12 upon the wall-plates and partition-plates of the casing; and the opposing doors in each cell or compartment are provided adjacent to their meeting edges with latch-levers 13 and U-shaped catches 14 whereby they may be manipulated, and retained in a closed or folded position, when desired. The corners of the casing are reinforced by vertically-disposed angle-beams 95 15; and the wall-plates 5 are braced and reinforced by exteriorly-disposed vertical ribs 16 arranged at suitable intervals. Upon the inner sides of the wall-plates 5 are mounted the longitudinally and transversely disposed shelves 17 and 17' which constitute the so-called "jack-seats", and which consist of 100 105

flanged beams which are supported partly upon the upper edges of the partition-plates 6 and 7; partly upon metallic brackets 18 which are bolted or otherwise firmly secured 5 upon the wall-plates of the casing, said brackets being preferably reinforced adjacent to their upper edges by angle-beams 19. Similar brackets 20 having reinforcing angle-beams 21 are secured upon the wall- 10 plates adjacent to the upper sides of the jack-seats to secure the latter against upward displacement. The doors 11, when open, may be retained by means of pins or bolts 22 inserted through suitable apertures 15 in the angle-bars 9 or in the jack-seats, according to the location of the doors.

In the operation of this device it is contemplated to force the casing downward by pressure derived from jacks of suitable construction which are mounted at suitable 20 intervals upon the shelves constituting the jack-seats or which are otherwise arranged in such a manner that pressure will be exerted upon the seats. The doors at the 25 lower ends of the cells or compartments are unlatched, but will normally remain in a closed position by gravity. As the device is being forced in a downward direction, the material that is to be excavated will be 30 pressed against the under sides of the doors, partially lifting and opening said doors and permitting a portion of the material to enter into the cells or compartments from which it may be readily removed; the intention being 35 to operate the jacks until the device is forced downward a distance of from four to twelve inches according to the nature of the material operated upon, after which the operation of the jacks may be temporarily suspended 40 while material is being removed from the cells or compartments. If necessary, the doors of some of the compartments may be latched and retained in a closed position while the device is being sunk or forced 45 downward, by the operation of the jacks; thus in the case of particularly difficult material, as when quicksand, in the language of the trade, is particularly "wicked", it may be found necessary or desirable to close 50 the doors of all of the outer cells or compartments, or those adjacent to the walls of the device, thus permitting the sand to enter only into the innermost compartments. The doors of the compartments, however, will be 55 operated and regulated entirely according to the nature of the soil or material that is being operated upon at the time being.

It is evident that the walls of the casing 60 will prevent the dirt from caving in while the work is in progress, thus greatly facilitating the work by obviating the unnecessary removal of material. It is also evident that

the walls of the excavation may be protected in any suitable manner while the work is in progress.

65

Having thus described the invention what is claimed is:—

1. A device of the class described comprising a casing having intersecting partitions forming a plurality of cells, angle-beams secured adjacent to the upper and lower edges of the partition-plates and adjacent to the lower edges of the wall-plates of the casing, and pressure-doors supported upon the angle-beams at the lower ends of the cells, said doors being arranged in pairs to open upwardly and provided adjacent to the meeting edges with fastening means whereby they may be secured in closed relation.

70 2. A device of the class described comprising a casing having intersecting partitions forming a plurality of cells, upwardly-opening doors adjacent to the lower ends of the cells, and shelves secured interiorly upon the walls of the casing, adjacent to the upper edges of the partitions.

75 3. A device of the class described comprising a casing having intersecting partitions forming a plurality of cells, upwardly-opening doors adjacent to the lower ends of the cells, shelves constituting jack-seats secured interiorly upon the walls of the casing adjacent to the upper edges of the partitions, and reinforcing brackets secured upon the walls of the casing adjacent to the jack-seats.

80 4. A device of the class described comprising a casing having partitions forming a plurality of cells, angle-beams adjacent to the upper and lower edges of the partitions and adjacent to the lower edges of the wall-plates of the casing, angle-beams at the corners of the casing, vertical strengthening ribs disposed at intervals exteriorly upon the walls of the casing, shelves constituting 90 jack-seats secured interiorly upon the walls of the casing and supported in part upon the upper edges of the partitions, reinforcing brackets for the jack-seats secured upon the walls of the casing, 95 upwardly-opening doors adjacent to the lower ends of the cells and supported by the angle-beams at the lower edges of the partitions and wall-plates, said doors being arranged in pairs and provided with fastening means adjacent to their meeting edges, and pins engaging apertures in the jack-seats and in angle-plates at the upper edges of the partitions to retain the door in position, 100 when open.

105 ALLEN BAGGS DOWELL.
